US00D549538S

(12) **United States Design Patent** (10) **Patent No.:** **US D549,538 S**
Lee et al. (45) **Date of Patent:** **** Aug. 28, 2007**

(54) **PORTABLE AIR NAILER**

(75) Inventors: **Sang-Chun Lee**, Gyeonggi-do (KR);
Gil-Sub Song, Incheon (KR);
Jong-Yeol Han, Gyeonggi-do (KR)

(73) Assignee: **Jeil Tacker Co., Ltd.**, Seoul (KR)

(**) Term: **14 Years**

(21) Appl. No.: **29/242,245**

(22) Filed: **Nov. 7, 2005**

(30) **Foreign Application Priority Data**

May 21, 2005 (KR) 30-2005-0016991

(51) **LOC (8) Cl.** **08-05**

(52) **U.S. Cl.** **D8/69**

(58) **Field of Classification Search** D8/14.1,
D8/49, 61-64, 65, 66, 67, 68, 69, 70; 81/57.11,

GB 2049899 S * 3/1995

Primary Examiner—T. Chase Nelson

(74) *Attorney, Agent, or Firm*—Lee, Hong, Degerman, Kang & Schmadeka

(57) **CLAIM**

The ornamental design for a portable air nailer, as shown and described.

DESCRIPTION

FIG. 1 is a front perspective view of the portable nailer showing our design;

FIG. 2 is front view thereof;

FIG. 3 is rear view thereof;

FIG. 4 is right side view thereof;

FIG. 5 is a left side view thereof;

FIG. 6 is a top view thereof; and,

FIG. 7 is a bottom view thereof.
